FILTER AND PUMP SUPPORT

Samuel Alsop, Milldale, Conn.

Application September 21, 1940, Serial No. 357,704

5 Claims. (Cl. 210—177)

This invention relates to a filter of the type having pads or parts needing replacement or servicing and to a support for the filter and its pads when being serviced, which is of such construction that it may be washed off easily.

Another object of this invention is to provide a simple and inexpensive yet rugged device of this class.

A further object is to provide a motor and pump for the filter carried out of the way on the underside of the filter support.

Still another object is to provide a convenient and attractive filter and support that is adapted to be easily moved where needed, kept neat and clean after servicing the filter, carry the pump for circulating the fluid to be filtered, yet capable of being washed with a hose without damage to the motor and without the expense of having a water-tight casing for the motor, and also adapted to be quickly moved to an out-of-the-way position when not in use.

Fig. 1 of the drawing shows the preferred embodiment of this invention in perspective.

Figs. 2 and 3 are longitudinal and transverse sectional views of the apparatus.

A filter and its casing 10 are mounted above a table top 11 on legs of non-corrosive material. The filter is of the type described and claimed in my copending application Serial Number 300,918, now Patent No. 2,313,612, filed October 24, 1939.

A motor 13 and a pump 14 on the motor shaft are mounted on the underside of the table top 11, flanges 15 being bent down to provide protection for the motor against a hose being played on the table top without danger of any substantial amount of wash water getting into the motor and without the necessity and expense of the motor being sealed against moisture. In other words an ordinary electric motor is found useful for this purpose. All exposed metal parts are preferably of some alloy which is non-corrosive to whatever liquid is being filtered so that parts of the filter may be supported on the table top 11 or the lower shelf without danger of any residual liquid on the filter parts being in danger of attacking or corroding the exposed metal parts such as the table top down-turned flanges 15 or the lower shelf 21 or the supporting columns 20 for the table top or the columns 12 for the filter.

Preferably a strengthening bead 16 is formed in the side flanges though not in the end flanges which are shorter and which are bent to overlap the ends of the side flanges, though of course if desired such strengthening bead may be pres-

ent on the end as well as on the side flanges. Of course, if desired, this bead 16 may be omitted or some other type of strengthening means used on the flanges or under them.

The pipe 17 leading to the pump 14 is connected to the outlet or other source of liquid to be filtered. From the pump 14 the fluid passes through one of the supporting legs 18 to the inlet of the filter, the column 18 being hollow for this purpose.

After passing through the filter the liquid leaves by the conduit 19 through the flexible connection shown in dotted lines. The legs or columns 20 supporting the table top 11 and also the motor and pump may have a bolt passing through them or may be suitably threaded or otherwise connected to the platform or shelf at each end. Not only are tools and parts of the filter capable of being placed on the table top but also some may be carried on the shelf 21 during the repair or servicing of the filter. The rollers 22 may be of non-corrosive metal or of suitable non-metallic molded plastic material that is not affected by whatever liquid is being filtered.

25 The device illustrated need not be necessarily mounted on such rollers but it is found they are convenient in moving the filter and its support to an out-of-the-way position when not in use. Numerous uses have been found for a filter mounted in the manner described, one such use being in connection with plating baths.

The top of the filter 23 is removable upon unscrewing the nut with the extension portions 24. The filter inlet or supply pipe 17 may be of 30 rubber or flexible hose as is that connected to the outlet 19.

After the wet filter parts have been replaced or serviced and the filter assembled again for further use, the table top 11 and the lower shelf 21 are easily kept clean and neat by washing them down with an ordinary jet of water from a hose or otherwise washing them off.

Beneath the table top 11 is a chassis frame supporting the sheet of non-corrosive metal and it is to this frame that the motor and pump are secured. Preferably the flanges 15 extend down far enough so that there will be no danger of the motor being damaged by water thrown onto or washed off the table top 11. The necessary wires for the motor and its connecting receptacle are located on the inner side of the flanges so as not to be injured by freely washing the shelf and table top. The flexible connections on the inlet and outlet side of the filter may be attached in the usual manner for rubber hose connections or they

may be quickly attached and detached in other ways well known in the art.

I claim:

1. A device of the kind described comprising a table having a plane top for supporting a filter and its casing, a motor and pump for the fluid being filtered secured to the underside of said table top, a platform below the table top and above which said motor and pump are spaced, supporting columns between said platform and table top, the sides of said table top being bent down and constituting protective flanges of depth sufficient to shield the vital parts of the motor and pump, the motor and pump being confined within the outer limits of the table and platform and a conduit having a passage extending from the pump through the table top for the flow of liquid to be filtered.

2. A device of the kind described comprising a table having a top of non-corrosive material, a filter and its casing carried by said table but spaced above the top thereof, a motor and pump for the fluid being filtered secured to the underside of said table top, the sides of said table top being bent down and constituting protective flanges of depth sufficient to shield the vital parts of the motor and pump, and columns for supporting said filter and casing above the table top, and a conduit having a passage connecting the pump and filter at least one of said last mentioned columns being hollow and constituting a part of the fluid passage between the filter and pump.

3. Portable means for filtering apparatus comprising a portable platform, a table top supported on said platform for supporting a filter in elevated and exposed position above the upper surface of the table top, a motor mounted on the under surface of the table top, a pump mounted on the under surface of the table top and operatively connected to the motor for moving liquid through said filter, and flanges extending downwardly from the table top for substantially housing the upper part of said motor and pump.

4. A filter support comprising a frame having a table top, a pump for moving liquid through the filter and a motor for driving the pump, the pump and motor being carried by the frame beneath the table top a conduit having a passage extending from the pump through the table top to conduct liquid to a filter above the top and a protective skirt depending from the edges of the table top and guarding the motor and the pump from water that may be spilled on the table top.

5. A device of the kind described comprising a table having a top with depending side and end flanges, a chassis frame supporting said top, a pump and an electric motor for driving the pump, means for securing the motor and pump to the chassis frame beneath the top within the margin of the flanges and means for conducting liquid from the pump upwardly through the table top, the flanges extending down around the vital parts of the motor and pump for preventing liquid from the table top from damaging the motor or pump.

SAMUEL ALSOP.
